UNITED STATES PATENT OFFICE.

JOSEPH BLANK, OF NEWPORT, KENTUCKY, ASSIGNOR TO J. A. FAY & EGAN COMPANY, OF CINCINNATI, OHIO, A CORPORATION OF WEST VIRGINIA.

SCROLL SAW.

Application filed January 29, 1923. Serial No. 615,569.

To all whom it may concern:

Be it known that I, JOSEPH BLANK, a citizen of the United States, residing at Newport, in the county of Campbell and State 5 of Kentucky, have invented certain new and useful Improvements in Scroll Saws, of which the following is a specification.

My invention relates to scroll saws, and has for its object the provision of novel and 10 compact means for applying tension to the saw-blade.

It is the object of my invention, further, to provide novel means whereby tension is applied to the saw-blade by coiled spring 15 means located in substantially their entirety close to the plane in which the saw-blade operates; further, to provide a step-pulley comprising pulleys of different diameters respectively having connection by 20 flexible means with the saw-blade and with coiled spring means located in compact relation with said step-pulley; further, to provide a bellows actuated by said spring means; further, to provide compact arrangements of tensioning devices whereby the 25 forces resisting movement of the saw-blade in one direction and exerting pulling movement upon the saw-blade in the opposite direction are exerted lengthwise of the saw-blade or parallel to the sides of the saw-blade throughout the lengths of said tensioning devices.

The invention will be further readily understood from the following description and 30 claims, and from the drawings, in which latter:

Fig. 1 represents a front elevation of a scroll saw embodying my invention.

Fig. 2 is a side elevation of the same.

Fig. 3 is a vertical section of my improved 40 device taken on the line 3—3 of Fig. 2.

Fig. 4 is a vertical section of my improved device taken on the line 4—4 of Fig. 1.

Fig. 5 is a vertical section of my improved 45 device taken on the line 5—5 of Fig. 2.

Fig. 6 is a horizontal sectional view taken on the line 6—6 of Fig. 2; and,

Fig. 7 is a detail in vertical section taken 50 on the line 7—7 of Fig. 3.

I have exemplified my invention as applied to a scroll saw comprising a goose-neck frame to support the tensioning means, although it is obvious that the tensioning means may be supported in different manner 55 by usual means now employed for support-

ing tensioning means of this character from above.

The scroll saw is exemplified as comprising a pedestal 11, in which a shaft 12 is journaled. The shaft may be driven in suitable manner, and has on it a crank-plate 13, on which there is a crank-pin 14. A pitman 15 has a bearing 16 at its lower end about said crank-pin, and is at its upper end articulated at 17 with a slide 18, slideable up and down in a guide 19 on the pedestal. The slide has on it a usual hook 21, for having the lower end of a scroll saw-blade 22 attached thereto.

The goose-neck frame 25 extends upwardly 70 from the pedestal, and is provided with a support 26. A bar 27 is slideable up and down in the support in a bearing 28, and is arranged to be clamped in adjusted positions by means of a bolt 29. A usual saw-guide 75 30 is at the lower ends of the bar in position to guide the rear edge of the saw-blade.

A casing 35 has a shaft 36 journaled there- 80 in in bearings 37. This shaft has a step-pulley thereon comprising a pair of pulleys 38, 39, of smaller diameter, and a pulley 40 of greater diameter shown located between said pair of pulleys. These pulleys may be 85 of wood.

A flexible connection, shown as a belt 41, is received about and secured at one of its ends to the pulley of greater diameter, as by means of a nail 42. The other end of this flexible connection is provided with a 90 usual hook 43, arranged to be connected with the upper end of the saw-blade. This connection is similar to the connection between the slide and the lower end of the saw-blade, and is instanced as comprising a pin 44 in the upper end of the saw-blade, the pin being located transverse to the plane of the saw-blade. The hook 43 is provided with a slot 45 in which the saw-blade is received, the respective ends of the pin being located 95 in the hook at the respective sides of said slot and of the saw-blade.

A pair of flexible connections, shown as belts 47, 48, are received about the pair of pulleys of smaller diameter, and are secured at one of their ends to said pulleys, as by means of nails 49, 50.

Coiled spring means have attachment with the outer ends of said pair of belts for exerting tension upon the same. These 110

coiled springs are located in compact relation with said step-pulley and are preferably located in their entirety close to the plane in which the saw-blade reciprocates to reduce vibration of the parts. The spring means are shown as comprising a pair of coiled springs 51, 52, shown as helical springs.

The means for attachment of the lower ends of the springs are shown as comprising bolts 53, 54, having conical heads 55 received in the lower windings of the respective springs. These lower windings are shown contracting toward the lower ends of the springs, as shown at 56, which are thus of volute form to hold said conical heads. The bolts have nuts 57 threaded thereover against the lower ends of the springs to securely hold the bolts by pressure of their heads and said nuts upon the lower ends of said springs. The lower ends of the bolts are provided with holes, through which rings 58 are received. The outer ends of the belts 47, 48, are passed through said rings to form loops 59, 60, for attaching the outer ends of said belts to said springs.

Bolts 63, 64, have conical heads 65 received in the upper contractingly wound ends of springs, which are thus of volute form, as shown at 66. The bolts have nuts 67 threaded thereover against the upper ends of the springs to securely hold the bolts by pressure of their heads and said nuts upon the upper ends of the springs. The bolts extend through holes in the upper wall of the casing and have nuts 68, 69, threaded thereover, for axially adjusting said threaded shanks and thereby adjusting the tensions of said springs.

A bellows 71 is provided, and, in the form shown, comprises heads 72, 73, connected by a flexible sheath 74 to confine the air. A bracket 76 is secured to the head 73, as by suitable screws, and is shown in the form of a fork comprising a shelf secured to the head, and depending tines bent at their lower ends and secured to the bolts 53, 54, by having holes in said bent lower ends through which said bolts pass, nuts 77 clamping said bent ends between the nuts 57 and 77.

A plate 81 has holes through which the bolts 63, 64, pass, the plate being secured between the nuts 67 and nuts 82 on said respective threaded shanks. It is secured to the head 72 of said bellows, as by means of suitable screws.

A hose 85 connects with said bellows and leads to a mouth 86 adjacent to the toothed edge of the saw-blade, for projecting puffs of air upon the work in advance of the saw-blade in order that the work in advance of the saw-blade may be free to the view of the operator. The pipe may contain a flexible portion 87. A suitable

clamp 88 may be provided at the lower end of the bar, or at any other suitable point, for adjustably positioning the mouth of the pipe with relation to the blade and work. The bellows is provided with a usual flap-valve 89 for admission of air to prevent suction at the mouth of the pipe.

The tensioning parts mentioned may be located in the casing 35, which may be of aluminum, and which is preferably adjustably positioned on the support toward and from the pitman in order to provide the proper tension upon the saw-blade and to accommodate the tensioning means to different lengths of saw-blades. The casing is adjustable up and down on a guide-way 91 on the support. A bolt 92 passes through a slot 93 in the support and a bearing 94 in the casing, a hand-nut 95 being received over the threaded end of the bolt for clampingly holding the casing in adjusted positions on the support by clamping the support and casing between the head of the bolt and the clamping nut.

A belt-guide 96 comprises a loop 97 about the belt 41, and is adjustably secured to the lower wall of the casing by means of a bolt 98 received through a slot 99 in the belt-guide and into a threaded hole into the lower wall of the casing.

My improved device forms compact means of light weight and few parts for providing tensions upon the scroll saw-blade, provides novel means comprising spring means whose axes are substantially parallel with the saw-blade or located close to the plane in which the saw-blade reciprocates, and provides means in which undue vibrations due to overhanging parts and mechanisms are avoided, and an arrangement in which the tensioning means are located within narrow compass and the tensioning stresses are confined to paths closely adjacent to the reciprocating movements of the saw-blade.

Having thus fully described my invention, what I claim as new, and desire to secure by Letters Patent, is:

1. In a scroll saw, the combination of a step-pulley comprising a pulley of greater diameter between the pair of pulleys of smaller diameter, a flexible connection about said pulley of greater diameter arranged for connection with the saw-blade, a pair of flexible connections about said pulleys of smaller diameter, a pair of coil springs having operative connections with said pair of flexible connections, and means for independently adjusting the tensions of said springs.

2. In a scroll saw, the combination of a step-pulley comprising a pulley of greater diameter between a pair of pulleys of smaller diameter, a flexible connection about said pulley of greater diameter arranged

- for connection with the saw-blade, a pair of flexible connections about said pulleys of smaller diameter, a pair of coil springs having operative connections with said pair of flexible connections, brackets extending from the respective ends of said springs, a bellows comprising relatively movable heads, and means for securing said respective heads to said respective brackets.
3. In a scroll saw, the combination of a pedestal, a table thereon, means on said pedestal under said table for reciprocating the saw-blade, a goose-neck fixed to said pedestal and comprising a head above said table, a casing, a step-pulley comprising a pulley of greater diameter between a pair of pulleys of smaller diameter journaled in said casing, a flexible connection about said pulley of greater diameter arranged for operative connection with said saw-blade, a pair of flexible connections about said pulleys of smaller diameter, a pair of spaced-apart coil springs in said casing having operative connections with said pair of flexible connections, means on said casing for independently adjusting said springs, and means for adjustably fixing said casing up and down on said head.
4. In a scroll saw, the combination of a table, means under said table for reciprocating the saw-blade, a head above said table, a casing adjustable up and down on said head comprising tension means, means for securing said casing to said head in adjusted positions, a step-pulley comprising a pulley of greater diameter between a pair of pulleys of smaller diameter journaled in said casing, a pair of coil springs, a flexible connection about said pulley of greater diameter having operative connection with said saw-blade, a pair of flexible connections about said pair of pulleys of smaller diameter, a fork extending from the lower ends of said springs and receiving said tension means between the tines of said fork, means on said casing for adjusting the upper ends of said springs, a bracket extending from the upper ends of said springs, and a bellows comprising heads respectively secured to said fork and to said bracket.
5. In a scroll saw, the combination of a table, means under said table for reciprocating the saw-blade, a head above said table, a casing adjustable up and down on said head comprising tension means, means for securing said casing to said head in adjusted positions, a step-pulley comprising a pulley of greater diameter between a pair of pulleys of smaller diameter journaled in said casing, a pair of coil springs, a flexible connection about said pulley of greater diameter having operative connection with said saw-blade, a pair of flexible connections about said pair of pulleys of smaller diameter, a fork extending from the lower ends
- of said springs and receiving said tension means between the tines of said fork, means on said casing for adjusting the upper ends of said springs, a bracket extending from the upper ends of said springs, a bellows comprising heads respectively secured to said fork and to said bracket, a pipe extending from said bellows, said pipe including a flexible section and a mouth adjacent to said saw-blade, and means for adjustably securing said mouth to said head with relation to said table and said saw-blade.
6. In a scroll saw, the combination of a table, a head thereabove, a casing, means for adjusting said casing on said head comprising a bolt, a step-pulley comprising a pulley of greater diameter between a pair of pulleys of smaller diameter and journaled in said casing, a flexible connection about said pulley of greater diameter arranged for connection with the saw-blade, a pair of flexible connections about said pair of pulleys of smaller diameter, a pair of spaced-apart coiled springs, a fork, the tines of said fork and the upper ends of said pair of flexible connections secured to the lower end of said spring, said bolt located in the space between said tines, a bracket secured to the upper ends of said springs, and a bellows comprising heads respectively secured to said fork and to said bracket, said pair of flexible connections, springs, fork and bracket inclosed in said casing.
7. In a scroll saw, the combination of a table, a head thereabove, a casing, means for adjusting said casing on said head comprising a bolt in said casing, a step-pulley comprising a pulley of greater diameter between a pair of pulleys of smaller diameter and journaled in said casing, a flexible connection about said pulley of greater diameter arranged for connection with the saw-blade, a pair of flexible connections about said pair of pulleys of smaller diameter, a pair of spaced-apart coiled springs, a fork, the tines of said fork and the upper ends of said pair of connections secured to the lower ends of said springs, said bolt located in the space between said tines, means on said casing for adjusting the upper ends of said springs up and down, a bracket and said last-named means secured to the upper ends of said springs, and a bellows comprising heads respectively secured to said fork and to said bracket, said pair of flexible connections, springs, fork and bracket inclosed in said casing.
- In testimony whereof, I have hereunto signed my name in the presence of two subscribing witnesses.
- JOSEPH BLANK.
